UNITED STATES PATENT OFFICE.

WILLIAM B. HAUTER, OF MORTON, ILLINOIS, ASSIGNOR TO A. F. MEYER MFG. CO., OF MORTON, ILLINOIS, A CORPORATION OF ILLINOIS.

GRAIN-DUMP.

1,273,854.

Specification of Letters Patent. Patented July 30, 1918.

Application filed March 20, 1916. Serial No. 85,308.

To all whom it may concern:

Be it known that I, WILLIAM B. HAUTER, a citizen of the United States, a resident of Morton, in the county of Tazewell and State 5 of Illinois, have invented new and useful Improvements in Grain-Dumps, of which the following is a specification.

This invention has reference to grain 10 dumps, and relates particularly to that type of dump in which dump-logs are the elements on which the vehicle rests containing the grain, and which are moved from a horizontal to an inclined position, so that the grain in the vehicle may be discharged, upon 15 the removal of the tail board or end gate from the vehicle.

One of the objects of the present invention is to provide a mechanism for operating the dump-logs to incline them at the desired 20 angle for dumping the grain, said operating mechanism including means for automatically locking the dump-logs in their various adjustable positions.

The invention has for a further object to 25 provide an operating means for dump-logs used inside an elevator or crib, including hangers suspended from a drive shaft on which the means for oscillating the dump-logs are mounted.

30 That the invention may be more fully understood, reference is had to the accompanying drawings, in which:

Figure 1 is a perspective view showing in dotted lines that portion of an elevating 35 structure in connection with which my invention is used and the invention shown in full lines applied thereto;

Fig. 2 is an elevation partly in section showing the driving parts of my invention 40 and the means for lowering and raising one of the dump-logs;

Fig. 3 is a detailed side elevation of an end of one of the dump-logs showing the manner of connecting the same for the 45 means of raising and lowering said dump-log;

Fig. 4 is an edge view of an operating wheel and the double pin crank for operating the same, and

50 Fig. 5 is a face view of the right hand side of what is shown in Fig. 4.

Like characters of reference indicate corresponding parts throughout the figures.

The present invention has reference to 55 that class of grain dumps shown and de-

scribed in the A. F. Meyer patent dated April 29th 1913, Number 1,060,349 and relates particularly to improvements upon the dump log operating and controlling means. Associated with the conveyer and elevator 60 structure are dump-logs, these dump-logs operating in recesses provided in the floor of the driveway and designed to receive the wheels of a vehicle and when tilted to move the vehicle into an inclined position, so that 65 when the tail-board or end-gate of the vehicle is moved, the grain or other material in the vehicle will be discharged into the chute to be conveyed to the leg or legs of the elevator and elevated to the distributor 70 in the upper portion of the elevator or crib to be distributed into suitable bins or compartments provided therein. One leg of the elevator is shown and designated by the numeral 1. This leg is connected with a boot 75 2, and communicating therewith is a trough or conveyer 3. The boot 2 and the trough 3 are preferably submerged in the ground in a suitable recess or compartment as shown in said Meyer patent and communicating 80 therewith, is a chute 4.

Extending at right angles to the chute 4 are walled compartments or recesses 5 in which the dump-logs 6 are located, pivotally connected thereto, as at 7.

The forward ends of the dump-log 6 have connected thereto, plates 8, which in turn are connected to endless chains or belts 9, each belt or chain 9 passing over a driving sprocket wheel 10 and a driven sprocket 90 wheel 11. The driving sprocket wheels 10 are carried on an operating shaft 12, said shaft being journaled in brackets or bearings 13 secured to one of the casings forming a binder for one side of the recess or compartment in which the chute 4 is located. The driven sprocket wheels 11 are carried on short shafts 14 journaled in bearings, formed on yokes 15, each of said yokes having stems fitting into a tube 16 by means 100 of which they are secured to said tubes, the opposite end of each tube having secured thereto a stem on a yoke 17, said last mentioned yokes having hubs or bearings to receive the operating shaft 12. The tube 16, 105 the yokes 15 and 17 constitute hangers supported by or hung on the operating shaft 12 and adapted to have oscillatory movement thereon to adapt themselves to the raising and lowering movement of the for- 110

ward ends of the dump-logs 6, and said dump-logs being connected to the endless belt or chains 9 which are passed around the sprocket wheels 10 and 11, may be operated 5 from the shaft 12 to lower and raise the dump-log 6, and by means to be described, moved to adjusted inclined positions and locked in such positions. The yokes 17 are positioned on the shaft 12 between pairs of 10 spaced brackets or bearings 13 to prevent endwise movement of the hangers on shaft 12 and the driving sprocket wheels 10 are disposed between the bearings on the yokes, as shown.

15 On one end of the operating shaft 12, is carried a sprocket wheel 18, the same being operated by a chain 19 driven by a sprocket wheel 20 on an operating shaft 21. The operating shaft last mentioned is journaled in 20 suitable boxings or bearings secured to the leg 1 of the elevator and disposed at convenient distances above the floor of the drive-way for convenience in the operation of the same by an operator. The shaft 21 25 has secured thereon, a wheel 22, said wheel formed with a plurality of spokes or spikes 23 producing teeth with which engage the pins 24, said pins constituting what is known in the trade, as a double pin crank and attached to or forming a part of a driving shaft 25, said shaft journaled in suitable 30 bearings or boxings on the leg 1 of the elevator. The driving shaft 25 is shown provided with a squared end to receive a hand 35 wheel 26 or a crank, whichever may be desired. The peculiar construction of the teeth of the wheel 22 and the double pin crank driving shaft 25 provides an operating means to enable an operator to transmit 40 motion with little power to the operating shaft 12 to lower and raise the dump-log 6, said double pin crank acting as a lock, when the pins 24 are in a horizontal position shown in Fig. 5, to prevent rotation of the 45 wheel 22, and the mechanism operated thereby, so that an operator upon actuating the

shaft 25 may impart movement to the shaft 21 and the operating shaft 12 through the connections between said last mentioned shafts to lower or raise said dump-log 6 and 50 whether by intention or not, the operator moves the double pin crank shaft 25 to the position shown in Fig. 5. Said pins 24 will assume this position and lock the wheel 22 in a position to retain the dump-logs in any 55 such adjusted position to which they have been moved.

It is obvious that various changes may be made in the construction and arrangement of the parts shown, without departing from 60 the spirit or scope of the invention, and I do not wish, therefore, to be limited except as the invention may be defined by the appended claims.

What I claim is:—

1. In a grain dump, in combination, a plurality of dump-logs pivoted between their ends, an operating shaft, a plurality of hangers each swingingly mounted at one end on the shaft and having its outer opposite 70 end free, wheels journaled at the opposite ends of the hangers, endless members supported by the wheels, and means connecting each endless member to the adjacent end of the respective dump-log, said hangers freely 75 swinging at their outer ends to permit easy operation of said dump-logs.

2. In a grain dump, an operating shaft, a dump-log, a hanger swingingly mounted at one end on the shaft and having its opposite end freely movable, sprocket wheels journaled at the opposite ends of the hanger, a chain passing about the wheels, said hanger and chain being disposed beyond and in opposing relation to the adjacent end of 80 the dump-log, a plate carried by said adjacent end of the dump-log and extended alongside of the chain, means connecting the plate to the chain, and means for locking the dump-log at any adjustment.

WILLIAM B. HAUTER.
